Primary Examiner — Catherine S Posthauer

(74) Attorney, Agent, or Firm — Daniel M. Cohn;
 Howard M. Cohn(57) **CLAIM**

The ornamental design for a vacuum stopper, as shown and described.

DESCRIPTION

FIG. 1 is a perspective view of a vacuum stopper showing the new design.

FIG. 2 is a front view thereof;

FIG. 3 is a rear view thereof;

FIG. 4 is a side view thereof;

FIG. 5 is a side view thereof, opposite the side view of FIG. 4;

FIG. 6 is a top plan view thereof; and,

FIG. 7 is a bottom plan view thereof.

The broken lines are shown for the purpose of illustrating parts of the article that form no part of the claimed design.

1 Claim, 7 Drawing Sheets(56)
